BULLDOZER

Cyril J. Bath, Shaker Heights, Ohio

Application April 8, 1932, Serial No. 604,000

3 Claims. (Cl. 153—48)

The present invention relates to metal working machines and more particularly to that type of machine known as benders or bulldozers. These machines are commonly used in machine and job 5 shops for various die operations, and bending and straightening operations on relatively heavy members such as structural steel, etc.

Machines of the type referred to usually consist of a bed, a die holder or end member on one end 10 of the bed, a reciprocal ram movable towards and from the end member, and means for reciprocating the ram including a crank mechanism. In operation the dies are set up between the end member and the ram by a tedious pack and try 15 method which consists of placing packing behind the dies until they are adjusted to the proper position for the particular job at hand. The maximum capacity or force of the machine is developed only for a short portion of the stroke near 20 the dead center of the crank and where a longer maximum power stroke is required to complete a job it is necessary to stop the machine and further pack the dies, etc., all of which takes considerable time, increasing the set up time required 25 for the job and decreasing the efficiency and usefulness of the machine.

An object of the present invention is the provision of a novel bulldozer which will be rugged in construction, easily adapted to perform different 30 jobs, and in which the setting up time is reduced to a minimum.

A further object of the invention is the provision of a novel bulldozer wherein the end member or die holder is adjustable along the bed or 35 frame of the machine towards and from the ram.

Other objects and advantages of the invention will be apparent to those skilled in the art from the following description of the preferred embodiment of the invention described with reference 40 to the accompanying drawings in which,

Figure 1 is a perspective view of a bulldozer embodying the present invention, with portions broken away to show certain features, and other features shown diagrammatically.

Fig. 2 is a side elevation of the machine shown in Fig. 1.

Fig. 3 is a plan view of a machine similar to that illustrated in Figs. 1 and 2 but showing anvils in place of die holders, and

Fig. 4 is a side elevation of the machine shown in Fig. 3.

Similar reference characters designate corresponding parts throughout the several figures of the drawings.

Referring to the drawings, the bulldozer illus-

trated is similar in construction to that illustrated and described in my copending application Serial No. 510,401, filed January 22, 1931. The frame indicated in general by the reference character A is preferably of welded plate construction and has ways 10 and 11 formed on the upper side thereof. A housing 12 formed on one end of the frame encloses and supports the main driving mechanism which may be of any conventional construction and forms no part of the present invention. 5 10

A ram 15 provided with a die holder 16 welded or otherwise secured thereto is slidably supported on hardened and ground steel wearing plates 13 fixed to the ways 10 and 11 in any suitable manner. Adjustable gibs carried by the ram 15 and indicated in general by the reference character 14 are employed for adjusting the bearings of the ram. The particular construction of the ram so far described forms no part of the present invention and is clearly illustrated in the above mentioned co-pending application. The ram is reciprocated longitudinally of the ways 10 and 11 by means of pitmans 17 and 18, pivotally connected to a shaft 19 supported therein and to 20 cranks 20 on bull gears 21 and 22 carried on a shaft 23, at opposite sides of the housing 12. The bull gears are driven from pinions 27 in a well known manner and are provided with a plurality of apertures 28 in which the cranks 20 may be 25 attached. In operation the load comes on the teeth of the bull gears only for a short part of the circumference and the wear is concentrated at this point. By moving the cranks 20 to different positions the wear is distributed about the circumference of the gears thus increasing the life of the same. As illustrated the bull gears 21 and 22 are provided with two apertures 28 spaced 180° apart, thus permitting the cranks 20 to be transferred from the positions shown to the other 30 35 40 apertures after one part of the gears has become well worn, but it is understood that more than two apertures may be used, thus still further increasing the useful life of the bull gears.

An end member 35 built of welded steel plates 45 is slidably supported in the bed or frame A and adjustable towards and from the ram 15 by means of parallel screws 36 and 37 rotatably supported at one end in a cross plate 38. Collars 39 and 40 prevent longitudinal movement of the screws which are threaded at their other ends into elongated nuts 43 positioned in openings in the end member 35 and non-rotatably secured therein by wedge blocks 45. Worm wheels 47 and 48 keyed to the screws 36 and 37 respectively are continuously in 50 55

mesh with worms 49 and 50 on a shaft 51. The shaft 51 is rotatably supported in suitable bearings, formed in housings 52 and 53 supported by the screws 36 and 37 etc. enclosing the worm and worm wheels, and is adapted to be rotated in either direction by a reversible electric motor 54 through a flexible drive 55. The motor is preferably controlled from a push button located at any desired place about the machine. From the foregoing description it will be apparent that the end member 35 can be quickly and easily adjusted to any desired position relative to the ram. The end member 35 carries a die holder 56 either formed integral therewith or, as illustrated, detachably secured thereto. A tongue 57 on the bottom of the die holder 56 engages in a groove 58 in the end member 35 and assists in holding the parts in their relative positions.

In Figs. 3 and 4 the machine is illustrated as set up for a bending operation. The die holders 16 and 56 are replaced by anvils 60 and 61. The anvils 60 are slidably supported by a member 62 secured to the ram 16 and are movable towards and from each other by a shaft 63 provided with right and left-hand threads 64 and 65. A hand wheel 68 is provided for rotating the shaft 63. The anvil 61 has a tapered lower end 69 which fits into a suitable aperture in the end member 35. The reference character W indicates a work piece.

It will be apparent from the foregoing description that I have provided a machine with a plurality of novel features. The movable end member permits the job to be set up in a minimum time and the long screws which take the thrust of the ram have sufficient elasticity or give to prevent breaking of the frame etc. when the machine is worked above its capacity. This feature is of considerable advantage because of the rapidity with which the force of the ram increases as the crank approaches dead center. If the dies are too close, even though this distance be small, machines of this type are subject to tremendous overload. While the machine illustrated is built up of welded steel plates, it is understood that other constructions may be employed such as cast members etc.

The invention has been described with reference to the preferred embodiment but it is to be understood that I do not wish to be limited to the particular construction shown as the invention is capable of being embodied in various construc-

tions, and this application is intended to cover any and all variations, uses or adaptations thereof as come within knowledge or customary practice in the art to which it pertains, and I particularly point out and claim as my invention:

1. A bulldozer comprising a bed, a slide supported by said bed adjacent one end thereof, a nut carried by said slide, a screw shaft engaging said nut and extending longitudinally of said bed, means adjacent the end of said bed remote from said slide for preventing longitudinal movement of said screw shaft, a worm wheel keyed to said screw shaft, a shaft supported adjacent said worm wheel, a worm on said shaft engaging said worm wheel, and a reversible electric motor for rotating said shaft.

2. A bulldozer comprising a bed having a supporting surface at one end and below the upper surface of said bed, a ram reciprocally movable on the upper surface of said bed, means for guiding said ram during its movements, a die supporting member slidably mounted on said supporting surface and having screw threaded openings therein, rods screw threaded at one end for engagement with said screw threaded openings and secured at the opposite ends against longitudinal movement for moving said supporting member relatively and independently of said ram, and means for actuating said rods.

3. A bulldozer comprising a bed having ram supporting surfaces and adjacent one end die supporting surfaces located in a plane below the ram supporting surfaces, a ram slidably supported on said ram supporting surfaces, means connected to said ram for reciprocating the latter, a hollow die supporting member slidably mounted on said die supporting surfaces, longitudinally aligned sleeves positioned upon the opposite sides of said die supporting member and secured thereto and internally threaded, rods extending longitudinally of said bed and having one of their ends screw threaded for engagement with the screw threaded sleeves, the opposite ends of said rods being rotatably mounted in said bed beyond said ram and secured against longitudinal movement with respect to said bed, and means operatively connected to the secured ends of said rods for rotating the latter in unison whereby said die supporting member may be moved independently of said ram.

CYRIL J. BATH.
